Primary Examiner — Sandra Morris(74) *Attorney, Agent, or Firm* — Ann W. Speckman; Speckman Law Group PLLC**CLAIM**

The ornamental design for a liquid pouring device for mounting on bottles, substantially as shown and described.

DESCRIPTION

FIG. 1 shows an upper, front perspective view of a liquid pouring device for mounting on bottles embodying my new design including a three-dimensional bird providing a liquid pour spout;

FIG. 2 shows a front view of the liquid pouring device for mounting on bottles as shown in FIG. 1;

FIG. 3 shows a rear view of the liquid pouring device for mounting on bottles as shown in FIG. 1;

FIG. 4 shows a first side view of the liquid pouring device for mounting on bottles as shown in FIG. 1;

FIG. 5 shows a second side view of the liquid pouring device for mounting on bottles as shown in FIG. 1;

FIG. 6 shows a top plan view of the liquid pouring device for mounting on bottles as shown in FIGS. 1; and,

FIG. 7 shows a bottom plan view of the liquid pouring device for mounting on bottles as shown in FIG. 1.

The broken lines shown are included for the purposes of illustrating unclaimed portions of the article, including a bottle stopper and, where shown, form no part of the claim.
